(57) CLAIM

The ornamental design for a bat LED bucket, as shown and described.

DESCRIPTION

FIG. 1 is a front top left side perspective view for a bat LED bucket, showing my new design;

FIG. 2 front bottom right side perspective view of FIG. 1 thereof;

FIG. 3 is a front elevational view of FIG. 1 thereof, the rear elevational view being a mirror image;

FIG. 4 is a left side elevational view of FIG. 1 thereof;

FIG. 5 is a right side elevational view of FIG. 1 thereof;

FIG. 6 is a top plan view of FIG. 1 thereof; and,

FIG. 7 is a bottom plan view of FIG. 1 thereof.

The broken lines indicate unclaimed portions of the bat LED bucket and form no part of the claimed design.

1 Claim, 7 Drawing Sheets
